UNITED STATES PATENT OFFICE

103,486

DESIGN FOR AN EDGING STRIP OR SIMILAR ARTICLE

William L. Bonnell, Columbus, Ohio

Application October 29, 1936, Serial No. 65,588

Term of patent 14 years

To all whom it may concern:

Be it known that I, William L. Bonnell, a citizen of the United States, residing at Columbus, in the county of Franklin and State of Ohio, have invented a new, original, and ornamental Design for an Edging Strip or Similar Article, of which the following is a specification, reference being had to the accompanying drawing, forming a part thereof.

Fig. 1 is a perspective view of the edging strip or similar article showing my new design;

Fig. 2 is a vertical transverse sectional view thereof.

I claim:

The ornamental design for an edging strip or similar article, as shown.

WILLIAM L. BONNELL.
